UNITED STATES PATENT OFFICE.

WILLIAM P. BALLARD, OF WHITESVILLE, WEST VIRGINIA.

ENVELOP.

No. 895,940.

Specification of Letters Patent.

Patented Aug. 11, 1908.

Application filed June 3, 1907. Serial No. 376,975.

To all whom it may concern:

Be it known that I, WILLIAM P. BALLARD, a citizen of the United States, residing at Whitesville, in the county of Boone and State of West Virginia, have invented certain new and useful Improvements in Envelops, of which the following is a specification.

This invention relates to envelops.

One object is to provide an envelop that cannot be opened without detection.

Another object resides in the provision of an envelop embodying two separate and distinct pockets.

With the above and other objects in view the present invention consists in the combination and arrangement of parts hereinafter described, illustrated in the accompanying drawings and particularly pointed out in the appended claims.

20 In the drawings:—Figure 1 is a plan view of a blank from which my envelop is formed. Fig. 2 is a plan view of the envelop partly folded. Fig. 3. is a plan view of the rear of the envelop with all except one of the sealing flaps sealed. Fig. 4 is a sectional view on the line 4—4 of Fig. 3. Fig. 5 is a rear view of the envelop in its sealed condition. Fig. 6 is a sectional view on the line 6—6 of Fig. 5.

Referring now more particularly to the accompanying drawings, the reference character 1 indicates the front or address side of my improved envelop and 2 the back thereof, the numeral 3 indicating a division or partition member provided with a sealing flap 4. 35 The front or address side of the envelop is provided with the sealing flaps 5 and 6 along its opposite longitudinal edges and a sealing flap 7 along its outer end, said flaps carrying dry adhesive substance, as shown.

40 To convert the blank shown in Fig. 1 into an envelop, the partition member 3 is folded along the line *a* upon the inner face of the back 2. The back 2 and partition member 3 are then folded along the line *b* against the inner face of the front or address side of the envelop, with the flap 4 of the partition member extended to lie against the flap 5. The flap 7 is then sealed to the outer face of the back 2, and the flap 6 subsequently sealed to said back, providing an envelop having two pockets, 8 and 9, one upon each side of said partition member. The flap 4 of the partition member seals the pocket 8, while the flap 5 seals the pocket 9.

55 The flap 4 is smaller than the flap 5 and

when a letter *c* is placed within the pocket 8 it may be sealed therein by the flap 4 independently of whether the larger flap 5 is secured to the back of the envelop. The larger flap may be sealed to the back of the envelop with or without a letter *d* in the pocket 9, and when sealed covers the smaller flap 4 and positively prevents access to the pocket 8 unless both flaps 4 and 5 are unsealed or severed from the body of the envelop or without otherwise tearing the envelop to such an extent as to indicate that the envelop has been opened or tampered with by an unauthorized person. The flaps 5 and 6 overlap when the envelop is sealed, 70 as shown in Fig. 6.

As shown in Fig. 5 the flaps 5 and 6 overlap a part of the flap 7, and I might state that the same form of envelop as that shown and described herein could be embodied in 75 a legal sized envelop without departing from the spirit of the invention.

It will be noted that two independent envelop pockets are produced, each accessible without reference to the other, and the two 80 pockets provided with one common closure at one end, namely the end closure flap 7. The two pocket envelop is thus produced from a single sheet of relatively small size and with the minimum of waste, as there is 85 no useless overlappings or false portions.

What is claimed is:—

An envelop comprising a front portion and a back portion with a partition portion folded between them to provide two independently accessible pockets with the partition portion forming the dividing means between the pockets and having a sealing flap said front portion having a relatively large sealing flap folded over said partition 95 sealing flap and projecting beyond the same, and said front portion having a closure flap at one edge folded over said back flap and a closure flap at one end folded over the back flap and forming an end closure to both of 100 said pockets, and said partition portion having a relatively small sealing flap foldable over the back portion.

In testimony whereof I affix my signature in presence of two witnesses.

WM. P. BALLARD.
